UNITED STATES PATENT OFFICE.

HAROLD EDGAR YARROW, OF SCOTSTOUN, GLASGOW, SCOTLAND.

HEAT INSULATION OF THE STEAM-GENERATING APPARATUS OF SUBMARINE VESSELS.

1,316,405.

Specification of Letters Patent. Patented Sept. 16, 1919.

Application filed May 7, 1917. Serial No. 167,041.

To all whom it may concern:

Be it known that I, HAROLD EDGAR YARROW, a subject of the King of Great Britain, residing at Scotstoun, Glasgow, Scotland, 5 have invented new and useful Improvements Relating to the Heat Insulation of the Steam-Generating Apparatus of Submarine Vessels, of which the following is a specification.

10 When a submarine vessel propelled on the surface by steam is submerged and the boilers are shut down, there is a large quantity of heat stored up in the boiler itself and in the highly heated brickwork for which there 15 are no ready means of dissipation and which may form a source of extreme discomfort to the crew.

According to the present invention, this heat is prevented from escaping from the 20 boiler and diffusing throughout the vessel by means of an outer casing surrounding the steam generating apparatus. The heat is rapidly dissipated by causing the air to circulate between the casing and the boiler and 25 to pass at some part of its circuit through a cooling device of well known type, where the heat is rapidly abstracted by a flow of sea water, or other cooling agent, and is conveyed outside the vessel. The arrangement 30 may be such that the circulation of the air only takes place in a compartment adjoining the boiler, which is highly heated.

In the accompanying drawings, various dispositions of the casing, cooling device 35 and means for circulating the air are shown, as applied for example, to a Yarrow water tube boiler. Figures 1, 2, 3, 4 are vertical cross sections through the boiler; Figs. 1^a, 2^a and 3^a are corresponding sectional side 40 elevations of the installation; Fig. 4^a is a sectional plan of the casing, and Fig. 5 a vertical cross section showing the position of the cooling device.

In all the figures similar parts are denoted 45 by the same letters of reference.

In Figs. 1 and 1^a, *a* is the steam drum; *b b* are water pockets; *c c* superheater drums, which may or may not be provided; *d* is the uptake and boiler casing; *e* the brick-pan; 50 *f f* steam generating tubes; *g* an air casing for the oil burners. In the example shown, an air casing *l* completely surrounds the boiler, the boiler mountings and the oil sprayers, but the invention is not restricted 55 to the disposition of the casing as shown; for instance, the boiler mountings, or the

oil spraying apparatus, or both, may be outside the casing. In the example shown, the casing is continued at *m* below the brick-pan *e*, so as to insulate and cool the incandescent bricks lining the pen. 60

At any convenient positions in the casing are disposed a fan *p* for circulating the air and a device *q* for cooling the air. The path of the circulating air is shown by the arrows; it enters the fan *p* by the intake *o*, traverses the cooling device *q*, passes down the trunk *n* and through openings *s, s* to the lower parts of the boiler, rises to the upper part of the boiler and flows around 70 the steam drum and uptake to the fan inlet *o*.

The cooling device *q* may comprise tubes traversed by the cooling medium, or conversely, the air may traverse tubes surrounded by the medium. The circulation of the medium may be effected in any suitable known manner by a pump or by convection. The cooling medium may be sea-water, or other liquid artificially cooled, or 80 the air may be cooled by passing over ice. 75

A diaphragm or baffle plate *r* causes the current of air to follow the path described. Sliding doors such as *k k* may be provided to give access to the boiler mountings and 85 oil sprayers or other parts, when the vessel is under steam.

It is obvious that the direction of circulation of the air may be opposite to that 90 shown.

In the modification shown in Figs. 2 and 2^a, two circulating fans *p* are shown driven by motors *z*. The water pockets *b b* are shown lagged and this lagging may be extended to other parts of the boiler. 95

In the modification shown in Figs. 3 and 3^a, a fan *y* usually provided for the employment of forced draft, is utilized to circulate the air between the casing *l* and the boiler. As shown, a steam motor *x* and an electric motor *z* are provided as alternative means for driving the fan, but one of these might be omitted. The air is cooled by the device *q*, as in the previously described constructions. By suitably arranged doors and shutters, the suction for the fan may be either from the open air or from the casing *l* and the delivery may be either into the stoke-hold or into the casing. 100

In the arrangement shown in Figs. 4 and 4^a, the cooling device *q* is placed in one of the ballast tanks *t* and is maintained at 110

a low temperature by the surrounding water. The air is drawn from the casing *l* by the fan *p* through the inlet *o*, delivered to the cooler *q* by the duct *v*, and returned 5 again to the casing by the duct *u*.

In Fig. 5, the cooling device *q* is placed in the inner hull, but the cooling water is supplied from the ballast tank *t* through the inlet pipe *i*₁ and delivered to the tank 10 through the delivery pipe *i*₂.

In this arrangement, when the vessel is on the surface and the ballast tank consequently empty the cooling device *q* is automatically drained.

15 Having thus described my invention and the best means I know for carrying the same into practical effect, I claim:—

1. In a submersible vessel, the combina-

tion, with a boiler; of a casing surrounding said boiler; means for drawing air through 20 the casing; and means for cooling the air drawn through said casing.

2. In a submersible vessel, the combination, with a boiler; of a casing surrounding said boiler; a fan for drawing air through 25 the casing; and pipes arranged in the path of the air current traversing said casing for cooling the air.

In testimony whereof I have signed my name to this specification in the presence of 30 two subscribing witnesses.

HAROLD EDGAR YARROW.
